United States Patent Office

Des. 212,804
Patented Nov. 26, 1968

212,804

TELEPHONE COVER WITH HANDSET
RETAINER OR THE LIKE

Stacy D. Blackman, 1106 Aversboro Road,
Garner, N.C. 27529

Filed Aug. 10, 1966, Ser. No. 3,411

Term of patent 14 years

(Cl. D26—14)

Fig 1

Fig 2

FIG. 3

FIG. 4

FIG. 1 is a perspective front view of a telephone cover with handset retainer or the like, showing my new design;

FIG. 2 is a rear perspective view of such design;

FIG. 3 is a front elevational view of the same; and

FIG. 4 is a front elevational view showing a modification thereof.

The broken lines are shown for illustrative purposes only.

I claim:

The ornamental design for a telephone cover with handset retainer or the like, as shown and described.
